CLAIM

The ornamental design for a phone, as shown and described.

DESCRIPTION

FIG. 1 is a perspective view of a first embodiment of a phone of the present design;

FIG. 2 is a front view thereof;

FIG. 3 is a rear view thereof;

FIG. 4 is a top view thereof;

FIG. 5 is a bottom view thereof;

FIG. 6 is a left side view thereof; and

FIG. 7 is a right side view thereof.

FIG. 8 is a perspective view of a second embodiment of a phone of the present design;

FIG. 9 is a front view thereof;

FIG. 10 is a rear view thereof;

FIG. 11 is a top view thereof;

FIG. 12 is a bottom view thereof;

FIG. 13 is a left side view thereof; and,

FIG. 14 is a right side view thereof.

The broken line showing of environmental features is for illustrative purposes only and forms no part of the claimed design.
